(57) **CLAIM**

The ornamental design for a shower tray as shown and described.

DESCRIPTION

FIG. 1 is a front elevational view of the shower tray showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view thereof.

The broken lines illustrate portions of the shower tray and form no part of the claimed design.

1 Claim, 7 Drawing Sheets
